UNITED STATES PATENT OFFICE.

ENOS STIMSON, OF MONTPELIER, VERMONT.

GRATER FOR CARROTS AND OTHER VEGETABLES.

Specification forming part of Letters Patent No. **57,213**, dated August 14, 1866; antedated July 30, 1866.

To all whom it may concern:

Be it known that I, ENOS STIMSON, of Montpelier, in the county of Washington and State of Vermont, have invented a new and Improved Machine for Grating Carrots and other Vegetables; and I do hereby declare that the following is a full, clear, and exact description of the construction and operation of the same, reference being had to the annexed drawing, and to the letters of reference marked thereon, making a part of this specification.

My invention consists in a cast-iron frame with a rotary grater operated by gears and crank.

To enable others skilled in the art to make and use my invention, I will proceed to describe its construction and operation.

A represents a cast-iron frame standing on a single base attached to a table by means of a thumb-screw, B, in such form and condition as to admit a pan to stand on the table under the grater C, which is attached to the end of a spindle or arbor, D, by means of a flange, E, the other end of said grater being open.

F is a cog-wheel with a crank, and turning on a stationary center and meshing with pinion G, which is held on spindle D by a pin, so as to be readily detached, leaving the grater free to be taken out.

H is a concave bar or rest holding the article against the grater, and partly shown through it.

Having thus described my invention, the operation of it will be understood by reference to the claim and drawing.

I claim no particular in distinction from the rest; but

What I claim is—

A rotary grater with an open end attached to the end of an arbor operated by gears and crank, in connection with the frame and rest, as described and for the purpose above specified.

ENOS STIMSON.
